UNITED STATES PATENT OFFICE.

JOHN STEPHENSON, OF NEW YORK, N. Y.

DESIGN FOR A CAR-TRUCK FRAME.

SPECIFICATION forming part of Design No. 18,551, dated August 21, 1888.

Application filed July 29, 1888. Serial No. 280,573. Term of patent 14 years.

To all whom it may concern:

Be it known that I, JOHN STEPHENSON, a citizen of the United States, and a resident of the city, county, and State of New York, have 5 invented a certain new and original Design for Frames for Car-Trucks, of which the following is a specification.

Figure 1 is a perspective view of a car-truck, illustrating my design for the frame thereof. 10 Fig. 2 is an inverted plan view, these two views being deemed necessary to fully illustrate my design.

The leading feature of my design is the shape of the frame, consisting of connected bars arranged as will now be described. 15

There are two outer parallel bars, 1 1, two parallel inner bars, 2 2, shorter than the outer bars, and two parallel intermediate bars, 3 3, shorter than the bars 2 2, and there are two 20 cross-bars, 4 4, extending between each bar 1

and the adjacent bar 2 and across the intermediate bar, 3, and there are two parallel cross-bars extending between the ends of the bars 3 3 across the bars 2 2. As thus designed, there is presented to the eye the appearance of a 25 rectangular frame, 3 3 5 5, lying between the bars 1 1 and crossing all the bars 4 2.

What I claim is—

The design for a car-truck frame herein shown and described, the same comprising the 30 outer bars, 1 1, inner parallel bars, 2 2, intermediate parallel bars, 3 3, and cross-bars 4 4 5 5, as set forth.

In testimony whereof I have signed my name to this specification in the presence of two sub- 35 scribing witnesses.

JOHN STEPHENSON.
